UNITED STATES PATENT OFFICE.

JABEZ H. GILL, OF PHILADELPHIA, PENNSYLVANIA.

IMPROVEMENT IN CARTRIDGE-MACHINES.

Specification forming part of Letters Patent No. 97,904, dated December 14, 1869.

To all whom it may concern:

Be it known that I, JABEZ H. GILL, of the city and county of Philadelphia, and State of Pennsylvania, have invented certain new and useful Improvements in Cartridge-Machines; and I do hereby declare that the following is a full, clear, and exact description thereof, reference being had to the accompanying drawings, making part of this specification, and to the letters of reference marked thereon, like letters indicating like parts wherever they occur.

To enable others skilled in the art to construct and use my invention, I will proceed to describe it.

My invention relates to machines for the manufacture of cartridges for fire-arms; and the invention consists in so constructing and arranging the various parts of the mechanism as to charge the cartridge case or shell with powder, insert the bullet, and crimp the shell thereon, and deliver the cartridge finished complete, all by one continuous operation, as hereinafter more fully explained.

Figure 1 is a top-plan view of my machine with the hopper removed. Fig. 2 is a vertical transverse section taken on the line $x-x$ of Fig. 1. Fig. 3 is a transverse horizontal section taken on the line $z-z$ of Fig. 4; and Fig. 4 is a side elevation, looking from the opposite side from that on which Fig. 2 is taken.

In constructing my machine, I make a circular frame consisting of two disks, A and B, united by uprights or standards C, the operating mechanism being mostly located between the parts A and B, while the operations are performed above the part A. The main driving-shaft G is located transversely between the parts A and B, as shown in Figs. 2 and 3.

In the center of the machine I mount a vertical shaft, E, which extends up through the part A, and carries on its upper end a rotating disk, D, which has, near its outer edge, a series of holes, in which are placed dies o, as represented in Fig. 2, the object of these dies being to receive the cartridge-shells, and to contract or crimp them on the balls at the proper time, as hereinafter explained.

Between the part A and the disk D is a circular block, A', of a thickness equal to the length of the shells, and of a diameter some-

what less than that of D, as shown in Fig. 2, there being a projecting ledge or flange, a, around the periphery of this part A', for the head of the shells to rest on, as shown.

Near one edge of the part A, I locate a rotating disk, N, (see Figs. 1, 2, and 4,) which is mounted on a shaft, N²; and in like manner, just above the disk D, at one side, I mount another rotating disk, O, mounted on and rotated by a shaft, O², each of these shafts having a pulley secured to their lower ends, as represented in Figs. 2 and 4.

On the horizontal or driving shaft G, I secure a bevel-gear, K, near one end, and this engages with a similar gear, K', secured to a vertical shaft located directly under the shaft G, and extending down through the part B, below which it has mounted on it two pulleys, from which cords or belts extend to and drive the shafts O² and N², as represented by dotted lines in Fig. 3. On this vertical shaft, below the gear-wheel K', I place a disk, J, which has projecting from its under face a stud or pin having on it a friction-roller, b, Fig. 3, which, as it rotates, comes in contact with an arm, I, pivoted upon the central shaft E. This arm I has pivoted to it a pawl, f, which engages in notches in the periphery of a ratchet wheel or disk secured rigidly to the shaft E, immediately under the arm, and just above the part B, as shown in Figs. 2 and 3, so that each revolution of the driving-shaft, the arm I, by engaging in the ratchet-wheel F, gives to the shaft E, and, consequently, to the disk D, a movement forward just equal to the distance from one hole in the disk to another, the parts being proportioned to effect this object.

Upon the back side of the part A, directly opposite the disk N, or nearly so, I place a frame or block, R, (see Figs. 1 and 2,) on which I mount the hopper R², for holding the powder, this hopper consisting of a circular inverted cone made of sheet-brass or any suitable material. Inside of this hopper I locate a paper funnel, R³, which has a tube leading from it to the hole in the bottom of the hopper, as shown in Fig. 2, the powder being placed in this paper funnel near the top of the hopper, so that in case of explosion the gases will readily escape into the air above, and thus prevent accident to the machine.

The front part of R projects forward over

the edge of the disk D, and has a hole formed through directly in line with the row of holes in the disk D, so that the latter shall pass under it, as shown in Figs. 1 and 2.

In the bottom of the hopper R², I place a slide, c, for shutting off the flow, and below that I place a charging-slide, d, which has through it a hole of proper size to contain the quantity of powder required to fill a shell. This slide d is operated by an elbow-lever, L, actuated by a cam, Q, on the driving-shaft G, as represented in Fig. 2, this cam having on one side two small projections, n, which impart to the elbow-lever, and thereby to the slide d, two shakes or slight movements as it is being charged from the hopper, so as to insure its being filled, there being also one such projection on the opposite edge of the cam, for the purpose of giving the slide another shake or vibration as it discharges the powder into the shell, so as to be sure that all the powder is discharged therefrom.

Just beyond the hopper, as shown in Figs. 1 and 4, I locate a post, Y, to which is secured a bell, J', the hammer h of the bell being pivoted to the top of said post. On this post I mount a sliding sleeve, X, having an arm projecting inward, and carrying a rod or plunger, t, which has a weight, C', secured to its upper end, said plunger with its weight sliding freely up and down in said arm.

In the side of the weight C' nearest the hammer h', I place a spring-pawl, o', as shown more clearly in Fig. 5, where the weight is shown in section; this pawl o' engaging with the projecting end of the hammer as the weight descends, thus raising the hammer; and if the weight descends far enough to let the pawl o' slip off the end of the hammer-lever, the hammer then falls and rings the bell. The distance, however, the weight C' descends is governed by the plunger t, which enters the cartridge-shell until it rests upon the powder therein. If, therefore, the shell contain the proper quantity of powder, the plunger t will rest on the top of the powder, and will not let the weight descend far enough to ring the bell; but if there be a deficiency of powder in the shell, then the bell will be rung, as described.

In order to adjust these parts with the requisite accuracy there is a screw, v, inserted, so as to bear against a shoulder on the pawl o', by which the latter can be adjusted in or out at pleasure, and thus cause it to slip off the end of the lever of the hammer sooner or later, as may be desired.

There is also a screw, e', inserted into the hammer handle or lever h', in such a position that as the hammer falls this screw e' shall strike upon the shoulder of the post Y, and thereby arrest its movement. By turning this screw e' in or out, the hammer may be adjusted so as to strike with more or less force, as may be desired.

Motion is imparted to the slide X, and

thereby to the weight C' and plunger t, by a vertical sliding rod, D', which rod is operated by a lever, h, which latter is operated by a cam, Q, on the driving-shaft G, as shown in Figs. 2, 3, and 4.

Immediately beyond the bell I locate a strong vertically-sliding shaft, M, which stands directly opposite the end of the driving-shaft G, as shown in Figs. 3 and 4. At the point opposite the shaft this rod M has formed in it or on it a cam-yoke, M², in which plays a crank-wrist, r, attached to the shaft G, there being in this case a disk with a pin, used instead of a crank, it being in effect the same as a crank. Upon the upper end of this sliding rod M, I secure a yoke, V', which projects inward over the disk D, in line with the series of holes therein, and this yoke, at its inner end, carries a plunger, q, which, as the rod M descends, is forced down into one of the holes in disk D, which happens to be brought directly under it at the time.

As shown in Figs. 1 and 2, the rotating disk O is located so as to carry the bullets u, which are placed upon it by an attendant, around over the hole in the disk D, and directly under the plunger q, so that as the latter descends it forces the bullet down through the hole in the disk into the mouth of the shell therein.

Directly below the plunger q, and in line with it, and of course in line with the shell in the disk D at that point, I locate another vertically-sliding rod, U, as shown in Figs. 3 and 4, its upper end just coming high enough, when down, to permit the cartridge-shells to be carried over it as they rest on the ledge a, and are brought around by the disk D. This rod U has an upward motion imparted to it by means of a lever, r', which is actuated by a cam, V, on shaft G, near its end, as represented in Figs. 3 and 4. By this upward movement of the rod U the cartridge directly over it is forced up into the taper die o, which thereby compresses the shell at its upper end, and thus secures the bullet firmly therein. Just beyond this rod U, I place a vertically-sliding tube, P, for withdrawing the finished cartridge from its die in the disk D. This tube P has an internal diameter sufficient to permit the cartridge to pass down through it, and at its upper end it has one side cut away sufficiently to let the cartridge-head enter sidewise into it as the cartridge is brought around to it by the disk D, the rear side of said tube projecting upward a little, and having an inward-projecting flange or lip extending around on its inner face, about half or two-thirds the diameter of the tube, as shown in Fig. 4, where a portion is broken away for the purpose of more clearly showing this feature. This tube P has a laterally-projecting arm, e, at its lower end, as shown in Figs. 2 and 4, the end of which arm rests in a vertical groove in the side of the rod M, as represented in Fig. 2.

As the rod M descends, its shoulder, at the upper end of this groove, strikes the arm e, and thereby carries the tube P down with it. As the tube P descends, its inwardly-projecting lip s, engaging over the rim of the cartridge, draws it out of the die o, when the cartridge, being thus loosened, falls of its own weight down through the tube, and is thus delivered at its lower end into a spout or receptacle of any suitable kind.

Transversely of the block A', I make a channel or opening, just below the ledge a, and place therein a slide, p, as shown in Fig. 2, this slide having one end projecting slightly over the edge of the rotating disk N, as shown in Fig. 1. This projecting end of the slide p has a projection on one side, thus forming a hook, as shown in Fig. 1. This slide is so arranged that as the disk N revolves and brings the cartridge-shells w around into the channel formed by the guides p' and v', the hook thereon engages behind the inner shell w, and draws it over the top of the rod T, which is located at that point, as shown in Fig. 2, so that as said rod is raised, as hereinbefore described, it pushes the shell w up into the hole in the disk D, as there shown.

The slide p is operated by a cam, 3, on the driving-shaft G, which cam, at the proper time, strikes against a pendent arm, l, (shown in Fig. 2,) the slide being pushed out by the cam, and drawn back by a spring. (Not shown.)

The mechanism and devices thus constructed are, of course, so timed in their various movements as to co-operate and bring each part into the required position and make it perform its movement at the proper instant.

As all the parts except the disks N and O are operated by pawls or cams, all except them move intermittently. Those parts N and O, being driven by cords or belts, of course have a regular and continuous movement.

The operation of the machine is as follows: Motion being imparted to it by hand or other power, as preferred, an attendant with one hand sets the cartridge-shells w on the disk N. This carries the shells around into the channel, as above described, where the hook on slide p draws them over the rod T, which pushes them up into the holes in disk D, which then moves forward, carrying the head of the cartridge over the ledge a, which keeps them from falling out. As the disk D rotates, the shells are carried around in front of the hopper, where they are successively supplied with the powder by the slide d, from whence they pass under the testing-plunger t, which gives notice of any deficiency in quantity by ringing the bell. From thence they pass around under the plunger q, which shoves a bullet down into the open mouth of the shell, the bullet

being placed on the disk O by the attendant's other hand, or by another operative, as preferred. As the plunger q rises, the rod U underneath rises also, and pushes the cartridge up into the smaller part of the die o, which thus compresses it tightly upon the bullet. The next movement of the disk D carries the head of the cartridge into the mouth of tube P, which pulls the cartridge out of the die and delivers it completed, so far as the operations of filling it with powder, testing it, putting in the bullet, and fastening it in are concerned.

It will thus be seen that I produce a very perfect, compact, and automatically-operating machine, which performs the various operations described in an expeditious and perfect manner.

Having thus described my invention, what I claim is—

1. The combination of the rotating disk N, slide p, and rod T, for feeding the shells into the carrier-disk D, said parts being arranged to operate substantially as described.
2. The combination of a carrier-disk, D, and the reciprocating powder charger or slide d, arranged to operate as set forth.
3. The combination of the carrier-disk D and the testing-plunger t, arranged to operate as set forth.
4. The combination of the carrier-disk D, provided with the dies o, the rotating disk O, and the bullet-plunger q, all arranged to operate as set forth.
5. The combination of the carrier-disk D, provided with taper or crimping dies o, and the sliding rod U, for fastening the bullets in the shells, substantially as described.
6. The combination of the disk D and the tube P, constructed and arranged to operate as described, for withdrawing the cartridges, as set forth.
7. The cam Q, provided with the projections n, arranged to operate the powder-slide d and impart thereto the vibratory movements, substantially as described.
8. The combination of the sliding plunger t and its weight C', having the spring-pawl o' attached, with the pivoted hammer h' and bell J', when arranged to operate as herein described.
9. The combination, in a cartridge-machine, of a carrier-disk, D, a powder charging and testing apparatus, a bullet feeding and pressing device, a crimping device, and a withdrawing apparatus, when the said several parts are constructed and arranged to operate substantially in the manner herein set forth.

JABEZ H. GILL.
